UNITED STATES PATENT OFFICE.

FRANÇOIS EMILE MAURICE DIARD, OF LEVALLOIS-PERRET, FRANCE.

DIVISIBLE AND ADJUSTABLE BRIDGE OR CRANE FOR LIFTING, CARRYING, OR SUSTAINING LOADS.

Application filed August 12, 1920. Serial No. 403,075.

To all whom it may concern:

Be it known that I, FRANÇOIS EMILE MAURICE DIARD, a citizen of the French Republic, residing at Levallois-Perret, France, 5 have invented certain new and useful Improvements in Divisible and Adjustable Bridges or Cranes for Lifting, Carrying, or Sustaining Loads; and I do hereby declare the following to be a full, clear, and exact 10 description of the invention, such as will enable others skilled in the art to which it appertains to make and use the same.

The matter of this invention is a divisible and adjustable bridge or crane, destined for 15 the use of lifting any kind of burdens, or the transportation of said burdens, if required. Said crane can be also used as a stand, or as a scaffolding trestle, as a pier or horse for a light bridge, as a pylon for supporting 20 a single rail runway or for fastening the cable of a bac, etc.

The design of said crane insures many advantages, as stated hereafter:

The pattern for loads up to 1.000-1.500 25 kgr. can be taken to pieces by only one man, that being done within a few minutes, without the use of any tool; the crane can be stably set up on any kind of ground or other surface, without requiring any preliminary 30 levelling or preparation of the said ground or surface.

Its height and width can be readily adjusted, according to the various requirements.

35 Many various combinations are possible, allowing its adaptation to any special cases.

The crane can be folded up, in view of facilitating its handling and transportation.

One form of this invention is shown by 40 the drawings, in which:

Fig. 1 is a perspective view of the whole crane, when assembled;

Fig. 2 is a front view of the head or joint of one tripod;

45 Fig. 3 is a profile view of the same head;

Fig. 4 is a front view of one branch of the tripods;

Fig. 5 is a profile view of said branch;

50 Fig. 6 is a front and end view of one branch fitted with a shoe provided with points;

Fig. 7 is a profile view of the same; Fig. 8 is a front view of a branch provided with an extension;

Fig. 9 is a front view of a branch with 55 rolling wheels;

Fig. 10 is a profile view of the same;

Fig. 11 is a vertical section of a scaffolding trestle, and Fig. 12 shows the horizontal girder of said trestle, which is fitted with a 60 timber floor.

The crane substantially consists of both tripods 1 and 2, which are connected by means of a girder or beam 3; said beam is made from rolled iron joist (I-profile iron), 65 and carries a hoist 4.

Each tripod consists of three branches 5, 6, 7 made from channel-iron; branches 5 and 6 are allowed to revolve within a common plane, and have respective pivots or axles 8, 70 9. Branch 7 is hinged perpendicularly to the plane of revolution of 5 and 6 and may revolve around axle 10.

The said axles 8, 9, 10 consist of bolts with 75 hexagonal heads, and have feathers preventing their rotation. Said bolts are provided with washers 11, hexagonal clamping nuts with handling wings 12, and retaining pins 13 prevent the nuts 12 from falling away.

By means of the said axles, the branches 80 5, 6, 7 are connected with a bracket 14, made from sheet iron, and having the shape of one of the two halves of a right-angled parallelopiped when cut into two parts by a sectional plane passing through the diagonals 85 of both the opposed smallest faces.

The flange 15 of said bracket has holes receiving the axles 8 and 9. A right-angled iron plate 16 is located perpendicularly to said flange 15, and fastened to it by means 90 of rivets. Said plate has a hole receiving axle 10. Both the bracket 15 and plate 16 are reinforced by riveted iron plates 17, 18, which are comparatively thick, in order to have the axles 8, 9, 10 held and guided like 95 within bearings; that also prevents the holes from becoming enlarged by wearing out.

In view of connecting more firmly the 100 branches 5, 6, with bracket 14, the flange of said bracket may also have arc-shaped openings 19, 20, through which pass additional bolts 21—22, fitted with hexagonal nuts hav-

ing wings allowing the said nuts to be tightened without a tool. The same device may be used for branch 7.

The upper flange 23 of the said bracket, 5 which carries the beam 3, is provided with a device for clamping the lower flanges of said beam. Said device substantially consists of two straps 24—25, respectively held in place by means of studs 26—27 with retaining pins; said straps are tightened by means of bolts 28—29 provided with hexagonal nuts having handling wings.

In order to facilitate the setting up of the beam 3, helical springs are arranged in such 15 a manner to push the straps 24—25 away from the flange 23, until the nuts of the bolts 28—29 have been tightened.

According to the various circumstances of employment, the said branches can be 20 lengthened by extension pieces 31, or receive end pieces 32 provided with points or spikes 33, or end pieces 34 having shoes 35 (said shoes can be plain shoes, or be provided with small points or corrugations), or 25 end pieces such as 36, fitted with wheels or rollers 37. The said end pieces may be fitted on the extension pieces, as it can happen that the branches, after having been lengthened by addition of extension pieces, 30 come to lie upon a weak or slippery ground, precisely for which case the special branch ends, such as 33, 34, 36 have been provided.

All the said extension or end pieces are made from channel iron and fit upon the 35 channel iron components of the proper branches 5, 6, 7. Suitable fastening devices are provided for.

Said fastening devices may be of any suitable kind; one of the simplest and strongest 40 of such devices consists of both bands 38—39, which are drawn over the extensions or end pieces, surrounding both said pieces and the branches; said bands can be tightened by means of screws 40; the suitable 45 length is secured by means of cleats 41, held by bolts passing through holes 42, drilled on both the extensions and end pieces.

The branches of the tripods may be prevented from slipping, by the use of a shackle 50 device, consisting either of two chains, or of any suitable combination of rigid tie-rods, which may be of any one of the known systems.

The crane, as described, is operated as 55 follows:

First, both the tripods are erected and set opposite one to the other; in this operation, care must be taken of opening the branches as wide as possible, in order to permit to 60 accede with the hands between the upper ends of the branches; after the bolts 21, 22 have been removed.

Then, the nuts 28—29 must be unscrewed and the lower flanges of the beam 3 are 65 passed under the straps 24—25, the nuts

28—29 are tightened and the branches of the tripods are brought together again. If slipping is liable to take place, the branches are to be connected each with the other by means of chains.

If the crane is to be used as a travelling crane, each branch of the tripods must be equipped with a wheeled end 36, which is clamped by the bands 38—39, after having the cleats 41 fastened at suitable place, according to the required height of the crane. Then, the tie-rods are adapted, which are intended to secure the stiffness of the whole system.

If the crane is to be used as a scaffolding 80 trestle, brackets or triangles 45 are clamped on the beam 3, and will serve to carry an element of timber floor 46.

The engine, as described, has many and various uses, a number of which are pointed 85 out hereafter.

If a wide space must be passed over, such as a canal, a wide ditch, or a hole, two cranes will be used together, one of which is erected on each side of the obstacle; these 90 cranes will be connected by means of an auxiliary beam extending over said obstacle; suitable tie-rods will be provided for, in order to obtain the required stiffness.

On an uneven ground, or a demolition 95 area, in short in every place where passage for cars could not be secured without painful and onerous clearing operations, a number of such cranes can be used supporting a 100 beam which carries the rail of a suspension runway. The components of the cranes, as above described, permit to erect the said cranes, either on hillocks, or on the holes between said hillocks, thus obtaining something like a platform, either horizontal, or 105 sloped according to the requirements. By this way, means of transportation can be secured in a very short time.

For holding a retaining cable, or the rope 110 of a bac or ferry-boat, the crane must be erected in such a way, that the beam be, as nearly as possible, perpendicular to the thrust on the rope. Said rope must be firmly fastened to the beam, and the branches of the tripods lying, relatively to the beam, on the same side as the rope must be fitted with the pick-shaped end pieces; said branches must be heavily driven into the ground, in order to resist firmly to the 115 thrust of the rope.

With a tackle-block or a hoist fastened on the beam, it will be possible to exert a draught, if required, for example, for moving a boat or the like.

It has already be stated that this crane 125 can serve as a travelling crane, or as a scaffolding trestle.

What I regard as new and desire to secure by Letters Patent is:

1. Apparatus of the character described 130

comprising in combination two tripods with pivotally attached legs, a beam having flanges, plates on each tripod adapted to engage said flanges and screws for tightening said plates.

2. Apparatus as in claim 1 wherein one or more of the tripod legs is provided with an extension slidably attached thereto.

3. Apparatus as in claim 1 wherein one

or more tripod legs is provided with a spiked shoe.

In testimony whereof I affix my signature in presence of two witnesses.

FRANÇOIS EMILE MAURICE DIARD.

Witnesses:

Wm. SAILLE,

CLEMENT S. EDWARDS.
